W. J. John
H. Wright Jr.

By J. J. J. J.
Att'y.

UNITED STATES PATENT OFFICE

WILLIAM JAMES JOHN, OF CROYDON, AND HERBERT WRIGHT, JR., OF LONDON, ENGLAND; SAID WRIGHT, JR., ASSIGNOR TO SAID JOHN

ELECTRIC FUSE

Application filed January 5, 1929, Serial No. 330,484, and in Great Britain January 6, 1928.

This invention relates to electric fuses for high tension circuits and to that type or kind wherein the fuse wire is so connected to springs that upon the wire melting its ends 5 are snatched apart by the springs.

In our fuse we enclose the wire in a cartridge and fit caps to the cartridge enclosure and pass screw devices through the caps. These screw devices are connected to the wire 10 inside the caps and to coiled blade springs outside the caps. When the fuse wire melts one screw device with its remnant of wire is jerked out of the cap to one side by one spring and the cartridge with the caps and the other 15 wire remnant is jerked to the other side by the other spring.

In the accompanying drawing:—

Fig. 1 is a part sectional side view of one of our fuses,
20 Fig. 2 shows a detail of one of the springs.

In this example a cartridge 1 of refractory insulating material has fixed to it caps 2 and 3. A screw device 4 passes through the cap 2 and is fixed to the cap by nuts 5. Another 25 screw device 6 is passed through cap 3 but is not attached to the cap. The inner ends of these screw devices are joined by fuse wire 7.

Screw device 4 is connected to spring 10 by nut 8 and washer 9 whilst screw device 6 is 30 connected in much the same manner to spring 11. Both springs are under strain and are held by the fuse wire. Immediately the wire melts spring 11 jerks screw device 6 through hole 12 in the cap 3 and carries the screw 35 and such remnant of wire as may still be attached to it in the direction of the adjacent arrow. Simultaneously with the removal of the said screw device, the cartridge as a whole is jerked to the other side as indicated 40 by line and dot. To quench the arc when the wire melts the cartridge may be filled with some material such as mica dust 13.

Each spring is mounted at its coiled end on a stud 14 having slot 15 to receive the inner end of the coil and suitably fixed as by 45 nuts 16 on bracket 17 which is slotted at 18 to receive the stud, said bracket being fixed to stop-bracket 19.

What we claim is:—

50 1. An electric fuse for high tension cir-

cuits including a cartridge enclosure, fuse terminals carried by the enclosure, a fuse wire connecting the terminals within the enclosure, and means for bodily moving the cartridge and one of said terminals in opposite 55 directions in the event of rupture of the wire.

2. An electric fuse for high tension circuits including a cartridge enclosure, fuse terminals carried by the enclosure, a fuse wire connecting the terminals within the enclosure, and spring members connected respectively to the cartridge and to one of said terminals and acting on the rupture of the fuse wire to separate and bodily move the cartridge and said terminal relative to each 60 other.

3. An electric fuse for high tension circuits, including a cartridge enclosure, a terminal fixed to one end of the enclosure, a second terminal arranged in and freely movable with respect to the other end of the enclosure, a fuse wire connecting the terminals within the enclosure, and spring members connected respectively to the enclosure and to the free terminal and acting in the event 70 of rupture of the fuse wire to bodily move the enclosure and free terminal in opposite directions.

4. An electric fuse for high tension circuits, including a cartridge enclosure, a terminal fixed to one end of the enclosure, a second terminal arranged in and freely movable with respect to the other end of the enclosure, a fuse wire connecting the terminals within the enclosure, and spring members 80 connected respectively to the enclosure and to the free terminal and acting in the event of rupture of the fuse wire to bodily move the enclosure and free terminal in opposite directions, said spring members being included 85 in the load circuit.

5. An electric fuse for high tension circuits including a cartridge enclosure, a cap for each end of the enclosure, a terminal fixed with respect to one of the caps, a second terminal freely slidable with respect to the other of said caps, a fuse wire connecting the terminals within the enclosure, and spring plates connected respectively to the 95 fixed terminal and to the freely slidable ter- 100

5 minal, said spring terminals acting on rupture of the fuse wire to move the freely slideable terminal and the cartridge enclosure relatively in opposite directions.

5 In testimony whereof we affix our signatures.

WILLIAM JAMES JOHN.
HERBERT WRIGHT, JR.
